APPARATUS FOR FABRICATING SHEET
METAL JOINTS

Ermal Cleon Fraze, 355 W. Stroop Road, Dayton, Ohio 5
Filed Oct. 30, 1962, Ser. No. 234,107
10 Claims. (Cl. 113—1)

This application is a continuation-in-part of my pending application, Serial No. 193,060, filed May 2, 1962, for "Sheet Metal Joint and Method and Means of Fabrication," now abandoned, which, in turn, is a continuation-in-part of my application, Serial No. 130,884, filed August 11, 1961, now abandoned.

This invention relates to a high speed multiple-stage apparatus for attaching devices to sheets of deformable material, and, more particularly, is directed to such an apparatus that fabricates the joints without using any fasteners whatsoever and without breaking the continuity of the sheets. While the invention is widely applicable for its purpose of attaching a member to a deformable sheet, it has special utility for those applications in which the sheet of deformable material is a fluid-confining wall. Since the continuity of the fluid-confining wall is not broken, the invention eliminates the problem of making the joint fluid-tight.

The invention has been initially embodied in an apparatus for the rapid continuous production of metal can tops that have manually removable tear strips whereby sealed cans incorporating the tops may be opened without the use of tools. This particular practice of the invention has been selected by way of example for the purpose of the present disclosure and will provide adequate guidance for those skilled in the art who may have occasion to apply the underlying principles to other specific purposes.

It is highly desirable to provide sealable cans, for example cans for fruit juices, beverages and various food products and articles subject to deterioration by the atmosphere, with the can tops or end walls scored to provide tear strips and with tabs attached to the tear strips to serve as handles for severing the tear strips to permit the can tops or end walls to be removed without the use of a can opener or like tools.

The problem of attaching the tab to the tear strip of a can top in a dependable manner without any possibility of incurring leakage at the joint is solved by forming a small part of the sheet metal of the tear strip into a hollow rivet element. The hollow sheet metal rivet element is inserted into an aperture of the tab and is then deformed into positive engagement with the tab. Since containers of this type must be produced at exceedingly low cost, the pressing requirement is to provide a completely automatic apparatus to convert blank can tops into finished can tops and simultaneously to produce the required tabs from sheet metal stock. More specifically, the requirement is to provide a fully automatic apparatus capable of carrying out the sequence of steps at the operating stations shown in the following flow chart:

2

It will be readily apparent to those skilled in the art that various well known types of conveyor mechanisms may be used to advance the can tops by stages through the sequence of can top operations and at the same time synchronously advance material for the tabs by stages through the sequence of tab operations. For example, a turntable may be used for either or both of the sequences, 45 the turntable being rotated intermittently to carry the work in process from operating station to operating station.

In the particular embodiment of the invention selected for the present disclosure, the can tops, blanked out and formed in advance, are fed to one end of a straight line conveyor to progress through the successive operating stations for the can tops. At the same time strip material for the tabs progresses through a second series of operating stations in a second straight line that intersects the first straight line at Station 4 where the tabs and the can tops are brought together.

The conveyor system for the can tops comprises a series of workholders carried by a pair of parallel continuous

conveyor chains which move intermittently to shift the workholders through Stations 1 to 5 in sequence. Each workholder carries two can tops and two sets of dies at each station operate on the two can tops simultaneously. In the meantime a strip of metal for the tabs advances step by step through progressive dies to produce the required tabs for each successive pair of can tops arriving at Station 4.

As will be explained, the invention solves the problem of positioning the workholders accurately at the different processing stations where high precision is essential and solves all of the other problems involved in carrying out both the can top cycle and the tab cycle at high speed in a continuous automatic operation. These other problems include: feeding the blank can tops to the workholder; safeguarding the apparatus from damage by faulty operation; operating the dies and conveyor chains in synchronism; indexing the conveyor chains for accurate intermittent movement of the workholders from station to station; using close fitting positioning jigs for the workholders where required without any possibility of the close fitting workholders sticking in the jigs; employing a progressive die for operating on a single strip of metal to produce two tabs simultaneously spaced to arrive simultaneously at Station 4; transferring the finished tabs to the can tops at Station 4; and discharging the finished can tops from the workholders at the end of the conveyor line.

The features and advantages of the invention may be understood from the following detailed description and the accompanying drawings.

In the drawings, which are to be regarded as merely illustrative:

FIG. 1 is a fragmentary perspective view of a can equipped with a tear strip as produced by the present apparatus;

FIG. 2 is a plan view of a blank can top after the first step of forming a dimple;

FIG. 3 is a plan view of a can top after the second step of forming the dimple into a hollow rivet;

FIG. 4 is a plan view of a can top after the third step of scoring the can top to form the tear strip;

FIG. 5 is a diagrammatic plan view showing how a tab is initially placed on the hollow rivet;

FIG. 6 is a plan view of the finished can top with the hollow rivet swaged into permanent connection with the tab;

FIGS. 7 to 11 are sectional views corresponding to adjacent FIGS. 2 to 6 respectively, FIG. 7 being taken along the line 7-7 of FIG. 2, FIG. 8 being taken along the line 8-8 of FIG. 3, FIG. 9 being taken along the line 9-9 of FIG. 4, FIG. 10 being taken along the line 10-10 of FIG. 5 and FIG. 11 being taken along the line 11-11 of FIG. 6;

FIG. 12 is an enlarged sectional view showing how dies cooperate at Station 1 to form a dimple in a blank can top;

FIG. 13 is a similar view showing how dies cooperate at Station 2 to form the dimple into a hollow rivet element;

FIG. 14 is a perspective view of the lower die in FIG. 13;

FIG. 15 is an enlarged fragmentary sectional view showing how the metal of a can top is scored at Station 3;

FIG. 16 is an enlarged sectional view showing how dies cooperate to spread the hollow rivet element slightly into temporary engagement with a tab at Station 4;

FIG. 17 is a similar view showing how dies cooperate at Station 5 to swage the hollow rivet element into permanent engagement with the tab;

FIG. 18 is a fragmentary sectional view showing how retractable fingers function to release blank can tops one at a time from a stack of can tops in a supply chute:

FIG. 19 is a simplified fragmentary elevational view showing a rack and eccentric assembly of the mechanism for actuating the fingers in FIG. 18;

FIG. 20 (first sheet) is a perspective view of a workholder and adjacent portions of two associated conveyor chains for carrying pairs of can tops through Stations 1 to 5;

FIG. 20a is a fragmentary sectional view of a portion of a workholder taken along the line 20a-20a of FIG. 10 and showing the construction of one of the retractable fingers for releasably holding a can top in the workholder;

FIG. 21 is a sectional taken along the line 21-21 of FIG. 29 showing how each successive workholder fits releasably into an accurate positioning jig at each of Stations 1 to 3;

FIG. 22 is a fragmentary sectional view showing how a shuttle plate reciprocates lower rams at Stations 4 and 5;

FIG. 22a is a perspective view of the shuttle plate of FIG. 22;

FIG. 22b is a fragmentary perspective view of a cam member that is mounted on the lower end of each of the lower rams in FIG. 22;

FIG. 23 is a fragmentary sectional view showing one of the three yielding pawls that supports a stack of the finished can tops in a discharge chute;

FIG. 24 is a side elevational view of the selected embodiment of the apparatus;

FIG. 25 is an end elevation of the apparatus as seen along the line 25-25 of FIG. 13;

FIG. 26 is an enlarged transverse section along the line 26-26 of FIG. 24 showing the mechanism for feeding blank can tops to the successive workholders;

FIG. 27 is a horizontal section as seen from below along the line 27-27 of FIG. 26 showing a portion of the mechanism for controlling the retractable fingers for feeding blank can tops to the successive workholders;

FIG. 28 is an enlarged fragmentary longitudinal section of the apparatus showing one of the sets of dies at each of the Stations 1 to 3;

FIG. 29 is an enlarged transverse section along the line 29-29 of FIG. 24 showing the two sets of dies at Station 1;

FIG. 30 is a similar transverse section along the line 30-30 of FIG. 24 showing the two sets of dies at Station 2;

FIG. 31 is a similar transverse section along the line 31-31 of FIG. 24 showing the two sets of dies at Station 3;

FIG. 32 is a horizontal section taken along the line 32-32 of FIG. 24 as well as along line 33-33 of FIG. 33 showing the progressive dies for forming the tabs at Stations A to E;

FIG. 33 is a longitudinal section along the line 33-33 of FIG. 32 showing the progressive dies at Stations A to E for forming the tabs;

FIG. 34 is a greatly enlarged portion of FIG. 33 showing a pair of cooperating coining dies at Station D for rounding the edges of the aperture in a tab;

FIG. 35 is a sectional view along line 35-35 of FIG. 24 showing the mechanism for transferring the finished can tops to two discharge chutes and also showing the mechanism for intermittently feeding strip material to the progressive dies for forming the tabs;

FIG. 36 is a transverse section along the angular line 36-36 of FIG. 24 showing the two lower rams at Station 4 and mechanism for actuating the shuttle plate to reciprocate the rams;

FIG. 37 is a longitudinal section along the line 37-37 of FIG. 36 showing the same mechanism and also showing the dies at Stations 4 and 5; and

FIG. 38 is a fragmentary perspective view showing how a nipping die at Station E transfers a finished tab to a can top at Station 4.

The successive operations on the can tops and tabs

FIG. 1 shows a can with a metal top, generally designated T, as produced by the apparatus of the present embodiment of the invention. The can top T is scored along a pair of lines 40 to form a tear strip 42 in a spiral-like formation circumscribing the periphery of the top so that removal of the tear strip in effect severs the top from the can. The tear strip 42 has a leading end indicated at 44 in FIG. 4 and one end of a thin tab 45 of a suitable metal is attached to the leading end of the tear strip to serve as a handle for manual removal of the tear strip.

The tab 45 is normally positioned in face-to-face engagement with the can top so that it does not interfere with normal stacking of the cans for shipment or display. The tab 45 is formed with a plurality of longitudinal ribs 48 to stiffen the tab and permit the tab to function as a relatively rigid lever for prying the leading end of the tear strip from the can top. Thus lifting the tab by its free end causes its opposite end to serve as a fulcrum for initiating the tearing action.

The tab 45 is formed with an aperture 50 as indicated in FIG. 5 to receive a hollow rivet element 52 that is formed in the sheet metal of the leading end of the tear strip 42, the hollow rivet element being best shown in FIGS. 3 and 8. Preferably, the aperture 50 is surrounded by an embossed rib 54 (FIGS. 16 and 17) which reinforces the rim of the aperture. It will be noted that both the aperture 50 of the tab and the hollow rivet element 52 are of elongated or non-circular configuration. In the finished can top T shown in FIGS. 1 and 6, the hollow rivet element 52 extends through the aperture 50 of the tab and is flattened and swaged outwardly to form a rivet head 55 as best shown in FIG. 17 for permanent and positive engagement of the leading end of the tear strip with the tab.

At Station 1, a relatively large circular dimple 56, shown in FIGS. 2 and 7, is formed in the blank can top T by the pair of dies shown in FIG. 12 comprising an upper female die 58 with a circular recess 60 and a lower male die 62 having a suitably tapered nose 64. The lower male die 62 is surrounded by a pressure pad 65 which clamps the metal of the can top against the upper die 58 with sufficiently light pressure to permit the sheet metal to creep radially inward towards the male die. The resulting dimple 56 which is much larger in area than the subsequently formed hollow rivet element 52 is only slightly thinner than the surrounding sheet metal of the can top.

At Station 2, the dimple 56 is formed into the hollow rivet element 52 by die means shown in FIGS. 13 and 14 comprising an upper female die 66 and a lower male die 68. The upper female die 66 has a cavity 70 and a leading face 72 and is surrounded by a pressure pad 74. The pressure pad 74 is under sufficient spring pressure to cooperate with a lower die block 75 to resist creepage of the sheet metal of the can top radially outward from the female die 66. The cavity 70 which is of the elongated cross-sectional configuration of the desired hollow rivet element 52 is dimensioned in depth to avoid restraining the upper surface of the transverse wall 76 that forms the top or outer end of the hollow rivet element 52.

The lower male die 68 serves as a forming mandrel so that when the two dies 66 and 68 close together they convert the relatively large dimple 56 into the smaller steep-shouldered hollow rivet element 52, the side walls of the rivet element being substantially perpendicular to the plane of the can top.

In the forming operation the two dies 66 and 68 function somewhat in the manner of conventional shrink dies to cause the metal of the previously formed dimple 56 to flow radially inward to result in thickening of the central portion of the dimple that is not restrained by the telescoping die surfaces. Thus the transverse wall 76 of a hollow rivet element 52 is increased in thickness as indi-

cated in FIG. 13, the thickness in this instance being substantially equal to the thickness of the tab 45.

At Station 3 an upper die 78 shown in FIG. 15 cooperates with a lower die 80, the upper die including a scoring element 82 to thin the metal of the can top along the pair of lines 40 to form the desired tear strip 42. The lower die 80 serves as an anvil with a flat upper surface to support the can top against the action of the scoring element 82. If the thickness of the can top T is of the order of 0.008 inch thick, the metal may be scored to a depth of 0.005 inch. At the same station, the upper die 78 cooperates with the lower die 80 to offset a portion of the sheet metal of the can top downward to form an elongated recess in the upper surface of the can top, which recess is designated 84 in FIG. 4. The parallel side walls of the recess 84 stiffen the sheet metal of the can top locally to facilitate the initial separation of the leading end of the tear strip from the can top by the leverage of the tab 45.

At Station 4 where a finished tab 45 is placed on the hollow rivet element 52 as indicated in FIG. 5, an upper nipping die 88 which severs a finished tab from a metal strip carries the finished tab downward to place the tab on the hollow rivet element 52. As best shown in FIG. 16, a can top T at Station 4 rests on a lower die block 85 which surrounds an upwardly protruding anvil member 86 that is dimensioned to fit snugly into the hollow rivet element 52. The upper nipping die 88 in FIG. 16 is cut away to conform to the embossed rib 54 of the tab 45 and incorporates a central ram member 90 that cooperates with the lower anvil member 86 to spread the rivet element 52 slightly in all radial directions for light engagement with the tab 45 to hold the tab in place as the can top is conveyed to Station 5.

At Station 5 the can top T with the tab 45 lightly engaged therewith is processed by a pair of dies in the manner indicated in FIG. 17. In FIG. 17 the can top T rests on a lower die block 92 that incorporates an anvil member 94 that protrudes upward into the interior of the hollow rivet element 52 in abutment with the inner surface of the transverse wall 76 of the hollow rivet. An upper die block 95 in FIG. 17 is cut away to clear the embossed rib 54 of the tab 45 and incorporates an upper ram member 96 to cooperate with the lower anvil member 94 for swaging the hollow rivet element 52 radially in all directions. The upper ram member 96 is driven forcibly against the transverse wall 76 of the rivet element 52 to squeeze and force the metal of the transverse wall outwardly by extrusion to form the previously mentioned rivet head 55 for firmly uniting the tab with the can top. Since the height of the hollow rivet element 52 is somewhat greater than the thickness of the tab 45 the die operation also tends to flare the side wall of the hollow rivet element 52 radially in all directions to force the side wall of the rivet element into pressural engagement with the outer rim of the aperture 50 of the tab. Preferably so much of the metal of the transverse wall 76 of the hollow rivet element is displaced radially by extrusion that the resultant peripheral bead or rivet head 55 is thicker than the final thickness of the transverse wall. Thus at Station 5 the can top is completed to provide the finished can top shown in FIGS. 6 and 11.

With reference to the fabrication of the tabs 45, a narrow strip of metal 98 is fed into the apparatus transversely thereof in the manner indicated in FIG. 35 and is processed by progressive dies at Stations A to E which are indicated by corresponding letters in FIGS. 32 and 33. At Station A spaced dies partially blank out two tabs 45 simultaneously leaving the two tabs connected to the metal strip 98 by narrow tongues so that the metal strip may serve as means to transport the tabs to the remaining Stations C to E in sequence.

At Station C the apertures 50 are punched in the tabs and at Station D the rims of the apertures 50 are coined or rounded. At Station E the previously mentioned nip-

ping dies 88 complete the blanking operation to sever the finished tabs from the metal strip and at this station the nipping dies carry the finished tabs downward to the previously mentioned Station 4 and serve as die means at Station 4 for lightly spreading the hollow rivet elements 52 into light or temporary engagement with the tabs.

General description of the apparatus

As shown in FIG. 24, the framework of the apparatus includes a base structure, generally designated 100, four columns 102 extending upward from the base structure to support fixed structure associated with Stations 1 to 3 for processing the can tops and four additional columns 104 extending upward for supporting the four corners of fixed structure associated with Stations 4 and 5 for processing the can tops and associated with Stations A to E for processing the tabs.

For the purpose of moving can tops in pairs from a feed station under a pair of feed chutes 105 through Stations 1 to 5 to a discharge station under a pair of discharge chutes 106, a series of dual workholders 110 of the construction shown in FIG. 20 are mounted at evenly spaced points on a pair of parallel conveyor chains 112. An upper run of the two conveyor chains extending from a pair of upper sprockets 114 to a pair of upper sprockets 115 forms a straight conveyor line through Stations 1 to 5, the return run of the two continuous conveyor chains extending from a lower pair of sprockets 116 to a co-operating lower pair of sprockets 118.

As shown in FIG. 20, each of the workholders 110 may be in the form of a relatively heavy rectangular plate with two circular apertures 120 formed with circumferential ledges or flanges 122 to serve as seats for a pair of the can tops. Each of the circular seats 120 is provided with a plurality of circumferentially spaced spring-loaded fingers 124 which serve the purpose of yieldingly retaining the can tops in the seats during the operations at Stations 1 to 5. The blank can tops are forced into the circular seats 120 at the feed station and are forced upward out of the seats at the discharge station. The operating Stations 1 to 5 are spaced five inches apart measured from center to center and the two conveyor chains are intermittently moved five inches to move the can tops to the five stations in succession.

At Stations 1 to 3 the upper dies of the previously mentioned die sets are fixedly mounted on an upper platen 125 that is supported by the four columns 102 and the corresponding lower dies are mounted on a lower reciprocative platen 126 that is slidingly guided by the four columns. At Stations 4 and 5 the previously described lower dies are mounted on upwardly extending rams comprising a pair of rams 128 (FIG. 36) for Station 4 and a similar pair of rams 130 (FIG. 37) for Station 5. The upper dies at Stations 4 and 5, as well as the upper dies at Stations A to E are mounted on an upper reciprocative platen 132 which is slidingly guided by the upper ends of the four columns 104. The lower reciprocative platen 126 for Stations 1 to 3 and the upper reciprocative platen 132 for Stations 4 and 5 and for Stations A to E are all actuated by a lower drive shaft 134 that extends longitudinally of the apparatus.

As shown in FIG. 24, a first sensing means in the form of a pair of photoelectric devices 135 is positioned between the feed station and Station 1 to sense whether or not a traveling workholder has an empty seat, a second sensing means 136 of the same character is positioned between Stations 3 and 4 for the same purpose and a third sensing means 138 in the form of a pair of micro-switches is located between Station 5 and the discharge station at the chutes 106 to detect whether or not tabs are assembled to the can tops as they approach the discharge chutes. If either of the first two sensing means detects that a workholder 110 lacks a can top or if the third sensing means ascertains that a tab is missing from a can top, the drive shaft 134 is immediately stopped.

All of the upper dies for progressively forming the tabs at Stations A to E are mounted on the reciprocative upper platen 132 as shown in FIG. 33 and the lower dies for these stations are mounted on fixed structure between the lower rams 128 and 130 and the upper reciprocative platen 132.

The metal strip 98 for forming the tabs 45 is supplied in a large roll and is fed intermittently to the apparatus in a well known manner by the mechanism shown in FIG. 35. An upper idler roller 140 under pressure from a coil spring 142 cooperates with a lower drive roller 144 that is driven at a constant speed by an individual motor (not shown). The drive roller 144 is journaled on an eccentric member (not shown) having an arm 145 for oscillation to move the drive roller into and out of driving contact with the underside of the metal strip 98. Thus the drive roller 144 periodically drives the metal strip by periodic upward pressure against the metal strip in opposition to the pressure of the idler roller 140.

The operating arm 145 is connected by a link 146 to a lever 148 that rocks on a central fulcrum 150. The lever 148 is connected by a connecting rod 152 to a crank 154 on a sprocket 155, the sprocket 155 being driven from a sprocket 156 (FIGS. 24 and 35) on the drive shaft 134 by means of a sprocket chain 158. The radial position of the crank 154 on the sprocket 155 is adjustable to adjust the throw of the crank and thereby adjust the length of the metal strip 98 that is advanced into the apparatus for each rotation of the drive shaft 134. FIGS. 24 and 35 also show a second sprocket 160 on the drive shaft 134 which drives a pump 162 by means of a sprocket chain 164 for circulating lubricant throughout the apparatus.

Considering the length of the metal strip 98 as divided into steps just long enough for blanking out one tab 45, the crank 154 is adjusted on the sprocket 155 for the drive roller 144 to advance the metal strip two steps on each of the revolutions of the drive shaft 134 that causes reciprocation of the various dies. Referring to FIG. 33, two upper punches 165 at Station A for partially blanking the tabs out of the metal strip 98 are two steps apart, i.e., considering the first of the two upper punches as operating on the first step along the length of the metal strip 98, the second punch operates on the fourth step. At Station B two sets of dies for forming ribs 48 on the tabs operate on two contiguous steps along the length of the metal strip 98. In like manner the dies at Station C for punching the apertures 50 in the tabs and the dies at Station D for coining or rounding the rims of the apertures 50 operate on two contiguous steps of the metal strip. The two nipping dies 88 at Station E are spaced apart with six intervening steps, the two nipping dies being thus spaced apart by the distance between the two hollow rivet elements 52 on the two can tops respectively on the workholder at Station 4. Pilot holes 166 (FIG. 32) are punched in the metal strip 98 at Station A to be used by suitable pilot pins (not shown) for accurately registering the metal strip with the dies at the remaining Stations B to E.

With the described arrangement of the progressive tab fabricating dies, finished tabs are punched out of all of the successive steps of the metal strip 98. Beyond Station E the remaining material of the metal strip is cut away two steps at a time by a punch 167 (FIGS. 33 and 36) and the pieces of scrap fall through an inclined chute 168 to a scrap box (not shown).

The mechanism for actuating the various dies

As shown in FIGS. 24 and 25, the drive shaft 134 which is journaled in suitable bearings 170 is driven by a variable speed motor 172 through the medium of a belt 174 and what is known commercially as a Fawick Fly Wheel Drive which includes a fly wheel 175 and an assembly comprising an air brake 176 and a clutch 178. The fly wheel 175 and the air brake-clutch assembly are mounted on the drive shaft 134 with an inclined link 180 (FIG. 25)

anchoring the brake shoes (not shown). Upon receiving a signal from any one of the three sensing means 135, 136 and 138, the clutch 178 is disengaged to release the drive shaft 134 from the fly wheel 175 and the air brake 176 is simultaneously actuated to bring the drive shaft to an instant stop.

Referring again to FIG. 24, the reciprocative lower platen 126 for Stations 1 to 3 is operated in a well known manner by two spaced eccentric assemblies 182 on the drive shaft 134, the reciprocative platen being connected to the two eccentric assemblies by two corresponding connecting rods 184 which pivot on a cross pin 185 of the platen.

To actuate the upper reciprocative platen 132 an overhead walking beam 186 is fulcrumed by a pivot 183 on fixed structure above the fixed platen 125 and is actuated by a yoke 190 which functions in the manner of a pull rod. As shown in FIG. 35 the upper end of the yoke 190 is connected to the walking beam 186 by pivot means 192 and its lower end is pivotally connected by a cross pin 194 to an eccentric assembly 195 on the drive shaft 134. The reciprocative platen 132 is operatively connected to the beam 186 by a pair of connecting rods 196 (FIGS. 24 and 35), the upper end of each connecting rod being pivotally connected to the walking beam by a corresponding pin 197 and the lower end of each connecting rod being connected to the platen 132 by a ball joint 198. As may be seen in FIG. 35, the yoke 190 straddles the upper runs of the two conveyor chains that carry the workholders 110 so that the yoke exerts balanced downward pressure on the die sets at Stations 4 and 5.

Referring again to FIG. 24 an intermittent drive means or indexer, generally designated 200, drives a shaft 202 carrying the two previously mentioned sprockets 114 for intermittently advancing the two conveyor chains 112 by increments of five inches on each revolution of the main drive shaft 134. The indexer 200 may be what is known commercially as a Ferguson Drive and may be driven by means of three sprocket chains 204 which connect three corresponding sprockets 205 on the drive shaft 134 with three sprockets 206 on the indexer.

The two lower rams 128 and 130 at Stations 4 and 5 respectively, are actuated by a drive means shown in FIGS. 22, 22a, 22b, 36 and 37. An upright lever 207 mounted on a central fulcrum 208 is oscillated by the upper reciprocative platen 132. For this purpose the upper end of the lever carries a follower 209 in the form of a roller that rides in an angular cam slot 210 that moves with the platen 132. The lower end of the upright lever 207 is connected by a short link 211 with a shuttle plate 212. By this arrangement the shuttle plate 212 makes one reciprocation for each reciprocation of the upper platen 132.

Each of the four lower rams 128, 130 has an inclined cam surface 213 on its lower end and each ram is provided on its lower end with a downwardly extending axial bolt 214 of stepped configuration which mounts a narrow cam block 215 on the lower end of the ram. As shown in FIG. 22b, each of the cam blocks 215 is formed with a pair of inclined cam surfaces 216 on its opposite sides respectively. Preferably suitable compression springs 217 (FIG. 36) act on the four bolts 214 to urge the four lower rams downward.

As shown in FIGS. 22a and 36 the shuttle plate 212 has a longitudinal slot 218 that straddles the cam blocks 215 of the two lower rams 128 and a second similar slot 219 that straddles the cam blocks 215 of the two lower rams 130. The shuttle plate 212 has two transverse inclined cam surfaces 220 and 221 on its upper side to cooperate with the cam surfaces 213 of the four lower rams to lift the rams when the shuttle plate is moved to the right as viewed in FIGS. 22, 22a and 36. In like manner, the underside of the shuttle plate 212 is formed with two transverse inclined cam surfaces 222 and 223 to contact the inclined cam surfaces 216 of the four cam blocks 215 to

lower the four rams with the assistance of the four compression springs 217.

The workholders and their operation

As best shown in FIG. 20 each of the rectangular workholders 110 that is carried by the pair of parallel conveyor chains 112 is mounted on skids 230 at its opposite ends respectively. Each of the two skids 230 is recessed as shown at its opposite ends for engagement and retention in a loose manner by two pairs of pins 232 that extend laterally from the two conveyor chains 112 respectively. By this arrangement the various workholders are held captive by the two conveyor chains but have substantial freedom for movement relative to the chains to permit the workholders to be lifted into operating positions at Stations 1 to 5.

As may be seen in FIG. 26 the opposite ends of the workholders 110 rest on the two conveyor chains 112 and the two conveyor chains in turn ride along parallel rails 234 as the workholders shift from station. On the return run of the two conveyor chains at the bottom of the apparatus the inverted workholders 110 ride along fixed rails 235 as shown in FIG. 25 and the two conveyor chains ride on two corresponding fixed rails 236.

Referring to FIGS. 20 and 20a, a ring 238 is mounted around the rim of each of the circular seats 120 to guide the blank can tops into the seats, each of the rings being tapered to form an inner circumferential guide surface 240. Each of the spring-loaded fingers 124 is mounted in a radial guideway 242 under the ring 238 and is formed with a retaining pin 244 that extends upward through a corresponding short radial slot 245 in the ring. In the absence of a can top in a circular seat 120 of a workholder 110, the fingers 124 are held at their radially inward limit positions by a garter spring 246 that is common to all three of the fingers. When a can top T is forced downwardly into a circular seat 120 of a workholder 110 the rim of the can top is guided by the guide surface 240 of the ring 238 to make contact with inclined cam surfaces 248 at the ends of the fingers 124. The can tops T act on the cam surfaces 248 to retract the three fingers 124 and then drop below the cam surfaces to be frictionally retained in the workholder seat by the fingers 124 under the pressure exerted by the garter spring 246. Thus the blank can tops T may be mounted on the successive workholders 110 by merely forcing the can tops downward to seat on the inner circumferential ledges 122 of the workholders.

At each of the Stations 1 to 5, the successive workholders 110 are lifted from the two conveyor chains 112 into seats that locate the workholder accurately relative to the dies at the station. At Stations 1 to 3 where exceedingly high accuracy is required in the positioning of the can tops, high precision jigs receive the workholders with close fit.

As shown, for example, in FIG. 31 illustrating Station 3, each of the positioning jigs includes an upper rectangular base plate 252 which is attached to the upper reciprocative platen 125. Two downwardly extending jig arms 254 at the opposite ends of the base plate 252 are spaced apart to confine with close fit the opposite ends of the successive workholders 110. In like manner as indicated in FIG. 21, two pairs of jig arms 255 extending downward from the base plate 252 make close fit with the opposite longitudinal sides of each successive workholder 110. The lower end of each of the six downwardly extending jig arms is cut away as shown in FIG. 31, to form a shoulder 256 for abutting the upper surface of a workholder and to form an adjacent shoulder 258 to fit against the edge of the workholder so that the six jig arms cooperate to form an accurately dimensioned and closely fitted rectangular jig seat. The lower end of each of the six downwardly extending jig arms 254 and 255 is additionally tapered as shown at 260 to guide the successive workholders into the jig seat.

At each of the Stations 1 to 3 two pressure pads 262 are mounted on the underside of the corresponding base plate 252 of the positioning jig to press downward on the two opposite ends of a workholder in the jig, the pressure plates being urged downward by suitable heavy springs 264 and being provided in a well known manner with suitable stop shoulders to limit their downward movement. The upward movement of the dies carried by the lower reciprocative platen 126 first causes a pair of centering pins 265 (FIG. 31) to enter a corresponding pair of centering bores 266 in the workholder 110 (FIGS. 20 and 21) to make sure the workholder is positioned to enter the jig seat. The upwardly moving workholder then encounters the tapered lower ends 260 of the six jig arms for final guidance into the jig seat as the lower dies reach their uppermost position.

As the workholders 110 enters the jig seats they retract the pressure pads 262 in opposition to the springs 264 and when the dies subsequently retract downward the two pressure pads function to dislodge the workholder from the work seat to permit the workholder to drop down to its normal position to rest on the two conveyor chains 112. For noise reduction the reciprocative platen 126 may be provided with pressure pads 268 at each of the Stations 1 to 3 to make contact with the skids 239 of the workholders to absorb the shock of impact with the skids. The springs 270 that urge the lower pressure pads 268 upward are stronger than the springs 264 of the upper pressure pads 262 to overcome the upper pressure pads and thus force a workholder into the jig seat.

It is essential that the workholder 110 be completely disengaged from the positioning jigs at the end of each operation to avoid interference with the subsequent advance of the workholders by the two conveyor chains 112. A feature of the invention in this respect is the provision of safeguards in the form of a pair of stripper arms 272 at each of the Stations 1 to 3 for positive ejection of the workholders from the jig seat in the event that the upper pressure pads 262 fail to carry out their function. The two stripper arms 272 extend through slots 274 (FIGS. 21 and 31) in the two jig arms 254 at the opposite ends of the jig seat and are timed to swing downward through the jig seat only after the upper pressure pads 262 have had time to dislodge a workholder in the jig seat.

Each of the stripper arms 272 is an arm of a bell crank 275 that is mounted on a pivot 276 carried by the fixed upper platen 125. The second downwardly extending arm of each bell crank 275 carries a follower in the form of a roller 278 that rides in a corresponding angular cam slot 280 in a block 282 on the lower reciprocative platen 126. Thus the two bell cranks 275 are oscillated automatically with correct timing in response to the reciprocation of the lower platen 126.

How the dies are mounted at operating stations 1 to 5

As shown in FIG. 28, the upper dies at each of the Stations 1 to 3 are mounted on the underside of the base plate 252 of the corresponding positioning jig and the base plate in turn is mounted on a corresponding upper support block 284. The three support blocks 284 are grooved for sliding engagement with a series of four flanged support rails 285 that are fixedly mounted on the underside of the fixed upper platen 125. Normally the support blocks 284 are suitably anchored against relative movement on the flanged support rails 285 but may be withdrawn from the support rails when desired to carry with them the corresponding upper die assemblies at the three stations.

At each of the Stations 1 to 3 the corresponding lower die assembly includes an adjustable tapered block 286 on which the lower die rests and which may be shifted longitudinally to raise or lower the lower die by exceedingly small increments. Each of the tapered adjustment blocks 286 rides in a tapered guideway 288 in a sup-

port block 289 and is controlled by an adjustment screw 290 which engages a threaded bore 292 in the tapered block. To hold each of the adjustment screw 290 against axial movement, the adjustment screw has a fixed radial collar 294 which is rotatable in a fixed retaining block 295. Each of the adjustment screws has a knurled head 296 for manual adjustment and carries a lock nut 298 for binding action against the corresponding retaining block 295.

At Station 1 as shown in FIGS. 28 and 29, the previously mentioned lower male die 62 extends through a vertical bore in the support block 289 to rest at its lower end on the tapered block 286 and is normally immobilized by a lateral set screw 300. The set screw 300 engages a tapered recess in the side of the male die 62 as shown to tend to cam the male die downward into snug abutment against the tapered adjustment block 286. The upper end of the lower male die 62 is surrounded by the previously mentioned pressure pad 65 which is formed with stop shoulders as shown and which is urged upward by suitable spring means 302.

The previously mentioned upper female dies 58 at Station 1 are fixedly attached to the corresponding jig base plate 252 by suitable screws 304. As heretofore noted the upward pressure of the lower pressure pad 65 created by the spring means 302 is relatively light to permit the sheet metal of the can tops to creep radially inward towards the lower male die 62 in the course of the forming operation.

At Station 2, as best shown in FIGS. 28 and 30, the two lower male dies 68 are mounted in upright bores in the previously mentioned lower die blocks 75 and each of the die blocks, which is of circular configuration, is mounted in a large circular bore in the corresponding lower support block 289 with both the lower male die and the die block resting on the corresponding tapered adjustment block 286. A lateral set screw 305 releasably engages a tapered recess in the side of the circular die block 75 to urge the die block downward by cam action.

Each of the two corresponding upper female dies 66 at Station 2 is slidably keyed in the corresponding jig base plate 252 and is urged upward against a headless adjustment screw 306 by a coil spring 308, the coil spring engaging an enlargement 310 of the die. A second headless locking screw 312 normally abuts the adjustment screw 306. The previously mentioned upper pressure pad 74 that surrounds the lower end of the female die 66 is formed with the usual stop shoulders and is urged downward by a plurality of springs 314, the spring means 314 exerting sufficient force to keep the metal of a can top from creeping radially inward towards the lower male die 68.

At Station 3, as shown in FIGS. 28 and 31, each of the lower anvils 80 is mounted in a large bore in the lower support block 289 of the Station with the lower end of the anvil resting on the corresponding tapered adjustment block 286. A lateral set screw 315 in the support block engages a tapered recess in the side of the anvil 80 to immobilize the anvil and to urge the anvil downward by cam action against the tapered adjustment block 286. The corresponding upper scoring dies 78 are anchored by screws 316 to the corresponding jig base block 252. As best shown in FIG. 28, each of the upper scoring dies 78 is surrounded by a stripper 318 which is urged downward by suitable spring means 320. It is apparent that the depth to which the sheet metal of a can top is scored is determined by the adjustment screw 290 that controls the elevation of the lower anvil 80.

At Station 4, as shown in FIG. 33 the two lower anvil member 86 and the two surrounding lower die blocks 85 are mounted on the previously mentioned lower reciprocative rams 128 respectively. Each of the lower die blocks 85 cooperates with a corresponding upper die block 322 which is mounted in fixed structure and which is

formed with a vertical transfer passage 324 to receive the corresponding reciprocative nipping die 88.

At Station 5, as indicated in FIG. 37 the lower die block 92 that surrounds the previously mentioned lower anvil member 94 for processing each of the can tops at the station is mounted on the corresponding lower reciprocative ram 130. The corresponding upper die block 95 and the previously mentioned upper ram 96 surrounded thereby are both mounted on the upper reciprocative platen 132.

How the dies are mounted at stations A to E

The dies for the five tab forming Stations A to E are mounted in the manner indicated in FIGS. 32 and 33.

At Station A, the previously mentioned two upper punches 165 for initially partially blanking out the tabs and an upper die block 325 that surrounds the two punches are carried by the reciprocative upper platen 132. A corresponding lower die block 326 is mounted on fixed structure and serves as a guide for a pair of lower shedders 328 that are urged upward by suitable spring means 330. When the upper punches 165 partially blank out the tabs, the tabs remain anchored to the metal strip 98 by tongues of metal and the tongues are bent downward by the punching operation. The purpose of the two shedders 328 is to restore the partially blanked tabs to the plane of the metal strip 98 after the punching operation.

At Station B, an upper rib-forming die 332 for operating on two adjacent tabs simultaneously is carried by the reciprocative platen 132 and cooperates with a complementary lower die 334 that is mounted on fixed structure. At Station C, upper die means including two piercing punches 335 are mounted on the upper reciprocative platen 132 and corresponding lower die means 336 is mounted on fixed structure. In like manner two upper coining dies 338 are mounted on the reciprocative platen 132 at Station D to cooperate with corresponding lower coining dies 340 that are mounted on fixed structure. As shown in enlarged FIG. 34 each pair of the coining dies 338 and 340 cooperate to round the rim of an aperture 50 in a tab 45. Preferably the rim is rounded to a radius of .005 inch.

At Station E, the two upper die blocks 322 of Station 4 have the added function of serving as female dies for cooperation with the two nipping dies 88. It may be noted in FIG. 33 that the leading ends of the two nipping dies 88 protrude downward beyond the other tab-forming dies on the upper reciprocative platen 132 so that the nipping dies sever the finished tabs 45 in advance of the operation of the other dies and then the nipping dies continue to move downward through the vertical passages 324 of the upper die blocks 322 to carry the finished tabs to the two waiting can tops at Station 5. As indicated in FIG. 3 each of the three nipping dies 88 is adapted to retain a severed tab by suction, the nipping die being formed with a longitudinal passage 342 for connection to a suitable vacuum pump (not shown). The exact configuration of the nipping die 88 and its relation to a tab is shown in FIG. 38.

The mechanism for feeding blank can tops

The mechanism for supplying blank can tops to the successive workholders 110 is illustrated by FIGS. 18, 19, 25, 26 and 27.

At the two feed chutes 105 shown in FIGS. 25 and 26, the two stacks of blank can tops are supported by the mechanism shown in FIG. 27. Each stack is supported alternately by a first upper set of three retractible radial fingers 344 and a lower similar set of three retractible fingers 345, the two sets of fingers operating alternately to support the stack. FIG. 18 shows how a stack is supported by the lower radial fingers 345 when the lower radial fingers are extended radially inwardly and the upper radial fingers 344 are retracted radially outwardly.

With the two sets of fingers in the positions indicated in FIG. 18 the lower fingers 345 support the stack but if the lower fingers 345 are retracted radially outwardly and the upper fingers 344 are simultaneously extended radially inwardly, the lower radial fingers will release and drop the lowermost can top and the upper set of fingers 344 will support the remaining can top of the stack. Thus each alternation of the two sets of fingers 344 and 345 releases one can top T to permit the can top to fall onto a lower yielding seat provided by three lower spring-loaded fingers 346.

When each of the successive workholders 110 arrives at the feeding station, a pair of vacuum pick-up cups 348 (FIG. 26) move upward through the empty circular seats 120 of the workholder to the two can tops that rest on the yielding seat formed by the lowermost set of radial fingers 346. The pick-up cups make vacuum engagement with the undersides of the can tops and pull the can tops downward into the seats 120 of the waiting workholder 110. It will be noted that the radial fingers 346 have inclined cam surfaces 350 at their leading ends to cause the fingers to be retracted by cam action on the part of the can tops. The pick-up cups 348 then drop below the workholder to avoid interfering with the subsequent advance of the workholder to Station 1.

As shown in FIG. 26 the two pick-up cups 348 are mounted on a yoke 354 that is connected to a vacuum source. The yoke 354 is slidably guided by fixed structure 355 and is connected by a pivot 356 to a push-pull rod 358 that is actuated by an eccentric assembly on the drive shaft 134.

The mechanism for actuating the two sets of fingers 344 and 345 alternately to release the blank can tops one at a time from the two feed chutes 105 is shown in FIGS. 35, 19, 26 and 27. As best shown in FIG. 19 a vertical rack 360 that is carried by the upper reciprocative platen 132 for reciprocation therewith meshes with a gear 362 on a short shaft 364. The shaft 364 which is journaled in suitable bearings 365 carries an eccentric assembly 366 which reciprocates a push-pull rod 368. As shown in FIG. 26 the push-pull rod 368 is inclined and is connected by a ball joint 370 to an arm 372 that is inclined downward from a vertical rocker shaft 374 to cause oscillation of the rocker shaft through a short angle. The push-pull rod 368 is made in two telescopic sections and is normally held extended to its full length by an enclosed compression spring 375 which yields to avoid damage in the event that the can top feed mechanism becomes jammed.

As shown in FIG. 27 a short rocker arm 376 on the upper end of the rocker shaft 374 reciprocates a bar 378 that is connected by ball joints to two rings 380 at the lower ends of the two feed chutes 105 respectively, the two rings being mounted on a base plate 381. Each of the two rings 380 is slidably confined on the base plate 381 to oscillate about its own axis and each of the three fingers 344 and the three fingers 345 associated with the ring is slidably confined to reciprocate radially of the axis of the ring. Each of the six fingers is provided with a pin 382 which slidably extends through a corresponding slot 384 in the ring. With the slots 384 associated with the three fingers 344 inclined in one direction circumferentially of the ring 380 and with the remaining three slots for the three fingers 345 inclined in the opposite circumferential direction, oscillation of the ring by the bar 378 causes the two sets of fingers to extend and retract alternately to release the can tops one at a time as hereinafter described.

The mechanism to discharge the finished can tops

Each of the two discharge chutes 106 at the discharge station is adapted to support a stack of finished can tops by means of yielding pawls in the manner indicated in FIG. 23. Each pawl 385 is mounted on a pivot 386 and is urged radially inwardly of the discharge chute by

a suitable compression spring 388. At the normal position shown in FIG. 23, each pawl 385 extends under the chute to engage and support the lowermost finished can top T in the stack. For this purpose the pawl 385 is of angular configuration as shown, the pointed end 5 of the pawl being formed with an inclined cam surface 390.

As shown in FIG. 35, positioned immediately under the discharge station is a yoke 392 carrying a pair of upwardly extending cylindrical bodies 394 to lift the finished can tops from the successive workholders 110. As the finished can tops are lifted upward they encounter the cam surfaces 390 of the three pawls 385 of FIG. 23 to retract the pawls until the newly introduced can tops pass beyond the pawls to become the lowermost can tops in the two discharge stacks. The yoke 392 is slidably guided by fixed structure 395 and is reciprocated by one arm of a lever 396 that is connected to the yoke by a link 397. The lever 396 is mounted on a pivot 398 and carries a follower 399 that rides in an eccentric cam groove 400 in a cam disk 401 that is operatively connected to the previously mentioned upper sprockets 206 (FIG. 24) that drives the indexer 200.

My description in specific detail of the selected embodiment of the invention will suggest various changes, 25 substitutions and other departures from my disclosure within the spirit and scope of the appended claims.

I claim:

1. In an apparatus of the character described for forming a hollow rivet in a sheet-like member to serve as 30 means for attaching the sheet-like member to an aperture object, the combination of:

means to advance the member through a sequence of operating stations;

a first forming means at one of said stations to form a dimple in said member;

a first holding means at said one station to hold the member during the dimple-forming operation and to permit slippage of the material of the member 40 radially inwardly toward the dimple area to minimize thinning of the material in the dimple-forming area;

a second forming means at a subsequent station to shrink said dimple into a hollow rivet having a transverse wall of substantially smaller area than the dimple without pressure on the area of the transverse 45 wall; and

a second holding means at said subsequent station to surround the dimple area to clamp the member under pressure during the shrinking operation to prevent slippage of the material radially outward away from 50 the dimple area to promote thickening of the material of the hollow rivet in the area of said transverse wall.

2. In an apparatus for attaching a first sheet-like member with an aperture therein to a second sheet-like member, the combination of:

means to advance the second member through a sequence of operating stations;

a first forming means at an early one of said stations to form a dimple in said second member;

a first holding means at said early station to hold the second member during the dimple-forming operation and to permit slippage of the material of the second member radially inward toward the dimple area to minimize thinning of the material in the dimple-forming area;

a second forming means at a later station to reduce said dimple into a hollow rivet having a transverse wall of substantially smaller area than the dimple without 70 pressure on the area of the transverse wall;

a second holding means at a later station to surround the dimple area to clamp the second member under pressure during the shrinking operation to prevent slippage of the material radially outward away 75

from the dimple area to promote thickening of the material of the hollow rivet in the area of said transverse wall;

means at a station to superimpose the first member on the second member with said hollow rivet of the second member extending through the aperture of the first member; and

means at a station subsequent to said later station to expand said hollow rivet with the rivet extending through said aperture of the first member thereby to engage the rivet with said first member.

3. An apparatus for joining a succession of first sheet-like member, each having an aperture, to a corresponding succession of second sheet-like members of deformable material without rupturing the members, comprising:

means to advance the second sheet-like members in succession to a succession of operating stations;

die means at one of said stations to form a dimple in each of the successive second members;

die means at a later station to form the dimples of the successive second members into hollow rivets of

lesser area in plan than the dimples;

means at a station subsequent to said later station to place the first sheet-like members on the successive second sheet-like members with the hollow rivets extending through said apertures;

means at the last mentioned station to expand the hollow rivets slightly to retain the first sheet-like members on the second members for conveyance to a still later station; and

means at the still later station to deform the hollow rivets into permanent engagement with the first sheet-like members.

4. An apparatus for joining a first sheet-like member having an aperture of predetermined size in its plane to a second sheet-like member of deformable material without a break in the continuity of the second member, comprising:

means to advance the second member through a sequence of operating stations;

die means at an early one of said stations to deform said second member to form therein a hollow offset portion of a cross-sectional size to pass through said aperture and of a length greater than the thickness of the first member and with an outer transverse wall;

a die member at a station subsequent to said early station, said die member being dimensioned to fit into said hollow offset portion of the second member to engage the inner surface of said outer transverse wall of the hollow offset portion;

means at a station subsequent to said early station to superimpose the first member on the second member with said hollow portion of the second member extending through said aperture of the first member; and

means coacting with said die means for subjecting said transverse wall of the hollow offset portion to a compression force across its thickness to decrease the thickness thereof by displacing the material of the transverse wall radially outwardly and simultaneously forming an integral outwardly directed circumscribing bead having a wall thickness substantially greater than the decreased thickness of said transverse wall and overlying and engaging the rim of the aperture of said first member to effect the jointure between the first member and the second member.

5. In an apparatus of the character described for producing a succession of first sheet-like members with second sheet-like members joined thereto, the combination of:

means to advance the second members through a first

sequence of stations, including a first station, a second station and a third station;
means at said first station to form a dimple in each of the successive second members;
means at said second station to reform the dimples of the successive second members into hollow rivets of less area in plan than the dimples;
means at the third station to position the successive second members for the hollow rivets thereof to receive the first members;
means to advance sheet stock progressively through a second sequence of operating stations, including a final station in the region of said third station of the first sequence; and
die means at the stations of the second sequence to fabricate the first members out of the sheet stock with apertures in the first members to receive the hollow rivets of the second members;
said die means including a die at said final station operable in one stroke to sever a finished first member from the sheet stock, to carry the severed first member to said third station to position the severed first member on a second member at the third station with the hollow rivets of the second member extending through the apertures of the first member and to deform the hollow rivet into engagement with the surrounding rim of the aperture of the first member.

6. In an apparatus of the character described for producing a succession of first sheet-like members with second sheet-like members joined thereto, the combination of:

means to advance the second members through a first sequence of stations;
means in said sequence of stations to form hollow rivets in the second members;
means in said sequence of stations to position the successive second members for the hollow rivets thereof to receive the first members;
means to advance sheet stock progressively through a second sequence of operating stations, including a final station;
die means at the stations of the second sequence to fabricate the first members out of the sheet stock with apertures in the first members in the planes thereof to receive the hollow rivets of the second members;
said die means including a punch at said final station operable in one stroke to sever finished first members from the sheet stock and to carry the severed first members to said first sequence of stations to position the finished first members on the second members at the first sequence of stations with the hollow rivets of the second members extending through the apertures of the first members;
said punch having a recess to clear the peripheries of the hollow rivets; and
means in said recess of the punch to deform the hollow rivets into engagement with the surrounding rims of the apertures of the first members.

7. In an apparatus of the character described for producing a succession of first sheet-like members with second sheet-like members joined thereto, the combination of:

means to advance the second members through a first sequence of stations, including a first station, a second station, a third station and a fourth station;
means at said first station to form a dimple in each of the successive second members;
means at said second station to reform the dimples of the successive second members into hollow rivets with transverse end walls of less area in plan than the dimples;
means at the third station to position the successive

second members for the hollow rivets thereof to receive the first members;
means to advance sheet stock progressively through a second sequence of operating stations, including a final station in the region of said third station of the first sequence;
die means at the stations of the second sequence to fabricate the first members out of the sheet stock with apertures in the first members to receive the hollow rivets of the second members,
said die means including a punch at said final station operable in one stroke to sever finished first members from the sheet stock and to carry the severed first members on the second members at the third station with the hollow rivets of the second members extending through the apertures of the first members, said punch having a recess to clear the peripheries of the hollow rivets at the third station;
die means in said recess of the punch to deform the rivets lightly into engagement with the surrounding rims of the apertures of the first members for transportation of the first members by the rivets from the third station to the fourth station; and
means at said fourth station to squeeze the transverse end walls of the rivets across the thickness of the end walls to expand the hollow rivets into more effective engagement with the first members.

8. In an apparatus of the character described for producing a succession of first sheet-like members with second sheet-like members joined thereto by hollow rivets of the second members extending through apertures in the first members in planes thereof, the combination of:

means to advance said second sheet-like members in succession through a first sequence of operating stations in sequence;
means at said first sequence of stations to form in the successive second members hollow rivets with transverse end walls;
means in said first sequence of stations to place the successive second members in position to receive the first members;
means to advance sheet stock progressively through a second sequence of operating stations;
means to fabricate said first sheet-like members with apertures therein in their planes from said sheet stock in said second sequence of stations;
means to feed the first members with apertures therein to the first sequence of stations and to position the first members on the second members in said sequence of stations with the hollow rivets of the second members extending through the apertures of the first members; and
die means in said first sequence of stations to squeeze the transverse end walls of the hollow rivets across the thickness for radial extrusion of the material of the end walls to expand the hollow rivets into permanent engagement with the second members.

9. In an apparatus of the character described for producing a succession of first sheet-like members with second sheet-like members joined thereto, the combination of:

means to advance said second sheet-like members in succession through a first plurality of operating stations in sequence including a first station, a second station, a third station and a fourth station;
means at the first station to form a dimple in each of the successive second members;
means at the second station to reform the dimples of the successive second members into hollow rivets with transverse end walls of lesser area in plan than the dimples;
means at the third station to place the successive second members in position to receive the first members;
means to advance sheet material progressively through a second plurality of operating stations including a

final operating station in the region of the third station in a plane spaced from the first station; means to fabricate the first sheet-like members from said sheet material in said second plurality of stations including a punch at said final operating station; means to advance said punch through said plane towards said third station to sever the successive first members from said sheet material and to shift the severed first members from said plane to the successive second members at the third station to position the first members with the hollow rivets of the second members extending through the apertures thereof, said punch having a recess to clear the peripheries of the rivets; means in said recess of the punch to deform the rivets lightly into engagement with the surrounding rims of the apertures of the first members for transportation of the first members by the rivets to the fourth station; and means at the fourth station to additionally deform the hollow rivets into engagement with the first members.

10. A combination as set forth in claim 9 in which

the means at the fourth station comprises a pair of co-operating dies to squeeze the transverse end walls of the rivets for radial extrusion of the material of the end walls to expand the hollow rivets.
